JOHN HARVEY PEARSON, OF INDIANAPOLIS, INDIANA, ASSIGNOR TO ONEPIECE BIFOCAL LENS COMPANY, OF INDIANAPOLIS, INDIANA, A CORPORATION.

MEANS FOR MAKING ANNULAR BODIES OF PLASTIC MATERIAL.

1,196,974.

Specification of Letters Patent.

Patented Sept. 5, 1916.

Application filed August 7, 1912. Serial No. 713,813.

To all whom it may concern:
Be it known that I, JOHN HARVEY PEARSON, a citizen of the United States, and a resident of Indianapolis, county of Marion, 5 and State of Indiana, have invented a certain useful Means for Making Annular Bodies of Plastic Material; and I do hereby declare that the following is a full, clear, and exact description thereof, reference being 10 had to the accompanying drawings.

The object of this invention is to provide means for the satisfactory and efficient formation of polishing buttons or tools for making lenses and kindred uses. In the manufacture 15 of lens polishing buttons or tools it is used for compressing a plastic material in annular form upon a metal or solid base or holder. The metal base or holder is used for holding the polishing tool during its operation 20 and the plastic material, which is solidified by the compression, forms a highly desirable and successful polishing surface or means. Heretofore, difficulty has been had in forming or making a polishing button or 25 tool from such plastic material because of the difficulty of compressing it and forming it annularly and upon the metal base, so as to render the tool sufficiently economical in construction, and, what is of more importance, sufficiently efficient in operation.

The nature of the invention will be understood from the accompanying drawings and the following description and claims.

In the drawings, Figure 1 is a central vertical section through the device with the press plunger and the table support partially broken away. Fig. 2 shows a central vertical section of the lower part of the device above the table and partially broken away, with 40 the plastic material put in place to be compressed. Fig. 3 shows the same parts as Fig. 2 at the end of the pressing operation.

The object of the invention is to compress a polishing body 10 to solidify it satisfactorily and make it hard and dense enough and give it shape and also cause it to adhere effectively to a metal base plate 11, so that when the operation is finished said parts 10 and 11 will constitute together a polishing tool for polishing lenses and the like. The metal base 11 is used for holding the tool onto means for operating it and the polishing body 10 has an annular rib 12 which, during the operation, is brought into contact with the lens for polishing it. This pol-

ishing body is made out of a suitable plastic material including rouge, such as lens grinders use, bound together by tar or other suitable material so as to make a comparatively hard and durable polishing body. 60 Since only the annular rib 12 engages and polishes the lens, it is desirable that the polishing body 10 be also annular and that there be holes 13 through the central portion of the metal base 11 for the passage of the 65 water during the polishing operation.

The base 11 has in its upper surface an annular recess or cavity in which the body 10 is placed so that after the compression of the body 10 and its pressure upon the base 70 11, the two will be caused to adhere permanently together. The upper surface of the base plate 11 has a central recess surrounded by a vertical rib 14, which has the same diameter as the opening desired through the polishing body 10 and said recess extends for about half of the thickness of the plate 11, as shown.

There is a stationary table or bench 15 shown, above which a plate 16 lies and it has 80 holes in its upper surface to receive pins 17 from the base 11. In operation the plastic polishing body 10 is first put in place on the base 11 by hand, said polishing material being then soft and plastic. It is arranged on 85 the base 11 in crude form and in the annular recess in the base 11. Then the base 11 is laid in place upon the plate 16 and an annular casing 18 put in place around the base 11 and polishing body, as shown in Fig. 2, 90 said casing being separable from the plate 16.

After the foregoing the compressing means is operated. This consists of an outer cylindrical die 20 with the lower end of said 95 die fitting snugly and operating in the casing 18 and with the lower end formed so as to give the desired conformation to the upper surface of the polishing body 10. The outer die 20 is closed at its upper end and has two vertical slots about midway for the ends of a pin 24 which extends through the inner die 22 and limits the downward movement of said inner die relatively to the outer die. The inner die is of the same diameter 100 as the recess in the base 11 so that when said inner die descends, it will enter said recess and give proper form and size to the central opening of the finished polishing tool. For 105 that purpose the inner die is recessed some 110

what at its lower end and as it descends, it removes the superfluous inner portion of the polishing body and forces it down through the openings 13 or out of the way. The inner die is forced down by a spring 23, while the outer die is being actuated by the press plunger 21 above. This press plunger is actuated by suitable means, not shown, after the other parts are in position. As the outer die goes down, the inner die will move at the same speed until it reaches the bottom of the recess in the base 11. Then the inner die will stop its downward movement, while the outer die will move down as far as the material of the polishing body will permit. Then the degree of solidity or hardness can be determined more or less by the degree of compression brought about by the action of the outer die. The exact vertical thickness of the polishing body is not very material, as such tools can be used effectively whether of exactly the same thickness or not.

I claim as my invention:

1. Means for forming annular bodies of plastic material including a chamber, a bottom plate, a tubular casing thereon forming a chamber in which the plastic material is placed, a central die in said chamber and adapted to be forced through the plastic material, a tubular die surrounding said central die for compressing the material, and yielding means between said dies, whereby actuation of the tubular die will cause the simultaneous movement of the central die until it is stopped and after which said tubular die may be further moved to compress the material.

2. Means for forming annular bodies of plastic material which consists in a bottom plate and casing within which said plastic

material is located, a tubular die for shaping one surface of the plastic material, means for actuating said tubular die, said tubular die having vertical slots in it, a die 45 within said tubular die for forming a central opening in said body of plastic material, a pin extending laterally from said inner die into said slots, and a spring located between the inner and tubular dies arranged 50 so that the actuation of the tubular die will cause the spring to actuate the inner die.

3. Means for forming annular bodies of plastic material including a chamber, a base for the plastic material having an annular 55 recess for receiving material to be treated and a central recess, a central die adapted to move into said central recess, and a tubular die surrounding said central die for compressing the material, said dies being simultaneously movable.

4. Means for forming annular bodies of plastic material including a chamber, a base for the plastic material having an annular recess for receiving material to be treated 65 and a central recess, a central die adapted to move into said central recess, a tubular die surrounding said central die for compressing the material, and a spring between 70 said central die and tubular die, said dies being arranged so that when the tubular die is actuated, the central die will be moved to its limit and thereafter the tubular die can move independently of the central die until the compression is completed.

In witness whereof, I have hereunto affixed my signature in the presence of the witnesses herein named.

JOHN HARVEY PEARSON.
